UNITED STATES PATENT OFFICE.

ADOLPH WEBER, OF DETROIT, MICHIGAN, ASSIGNOR OF ONE-HALF TO
THOMAS S. CHRISTIE, OF SAME PLACE.

STEAM-RADIATOR.

SPECIFICATION forming part of Letters Patent No. 367,078, dated July 26, 1887.

Application filed May 27, 1886. Serial No. 203,423. (No model.)

To all whom it may concern:

Be it known that I, ADOLPH WEBER, of Detroit, in the county of Wayne and State of Michigan, have invented new and useful Improvements in Steam-Radiators; and I do hereby declare that the following is a full, clear, and exact description thereof, reference being had to the accompanying drawings, which form a part of this specification.

This invention relates to new and useful improvements in radiators for steam and hot water, and it has particular reference to that class of radiators composed of a number of like sections or loops; and the object of my invention is to improve the means in present use for connecting any desired number of sections into a nest, and to produce at the same time a perfect circulation through all the individual loops or sections composing the radiator; and to this end my invention consists in the improved construction hereinafter described, and shown in the accompanying drawings, of which—

Figure 1 is a horizontal central section through the base of a radiator of my improved construction. Fig. 2 is a vertical central section thereof with the bar connecting the sections through the base shown in elevation. Fig. 3 is a vertical central cross-section through one of the loops or sections detached. Fig. 4 is a perspective view of the bar which connects the individual loops or sections of the radiators. Fig. 5 is a sectional perspective view of the lower end of one of the radiator loops or sections.

It has been common to unite a plurality of radiator sections by means of tubes passed through the bases of the sections; but such construction did not extend the whole vertical height of the eyes through the loops, and did not provide for a circulation alternately through the loops. I provide a connecting-bar, which extends the whole vertical height of the eyes through the bases of the loops, and which divides the base into two steam-spaces, and said bar is also provided with lateral cut-offs, all as hereinafter set forth.

Are the sections composing the radiator. They are preferably made in the form of cast-iron loops, but may be of any other form adapted for this class of radiators.

C are hollow round bosses cast on one of the small bends of the loops, so as to form cylindrical eyes B, communicating with both legs of the loop. These bosses project on each side of the loops and are provided with suitable steam and water tight joints D, all so arranged that when the loops are placed or put together the cylindrical eyes B form a cylindrical steam and water tight base for the radiator, with which all the legs of the loops communicate.

E is a connecting-bar provided at one end with an apertured head, F, which forms a tight joint on one end of the base, and with a screw-nipple, G, which projects through the other end of the base and engages with a screw-cap, H, which forms a similar tight joint at the other end of the base. The bar E forms a vertical diaphragm through the base, so as to cut off communication between the lower ends of the two legs of each loop, with the exception of the restricted communication through the openings a, provided for at the bottom of the base in each loop. The bar E is also provided with the half-circular diaphragms I, which are so arranged that when the bar is in place they form alternating transverse cut-offs in the base upon opposite sides of the bar or diaphragm E.

It will be seen that with the loops constructed as described, and with a connecting-bar of the required length to fit the desired number of loops to be connected, the work of mounting a radiator (or dismounting either) is greatly simplified when compared with the present mode of connecting the loops together by means of screw-nipples; and, further, the novel and simple way of providing for a circulation by the peculiar construction of the connecting-bar materially reduces the cost of the radiator.

In practice, the radiator is connected with the steam or hot-water pipes in the usual manner, the head F and nipple G being for this purpose provided with suitable screw-threaded apertures leading into the base of the radiator; and, supposing the steam to enter through the aperture in the head F, it will be seen that after passing up through one leg and down the other leg of the first loop, it passes on one side of the diaphragm E into the second loop, and, circulating in the reverse di-

rection through said loop, it passes on the other side of the diaphragm E into the third loop, and so on in alternate directions through all the loops until it reaches the exit through the nipple G. The condense, which accumulates at the bottom of the base, passes through the openings *a* (which may be provided either as shown in full lines in the drawings, or by slightly cutting away the bar E, as shown in dotted lines in Fig. 2,) and finds its exit along the bottom of the base to the exit-pipe.

As the bar E has a fixed position in relation to the base, I preferably provide it with a feather, *b*, which fits into a corresponding recess and prevents said bar from being displaced.

I claim the bar E as a novel combination of diaphragms for producing the circulation in the loops irrespective of its additional feature of a connecting-bar, as other suitable means such as are in present use may be devised for that purpose; but it is obvious that by combining the two features in the manner described great simplicity is obtained. With 25 an even number of loops, as shown in the drawings, the apertures in the head F and nipple G have to communicate with the base of the radiator upon the same side of the bar E; but if an odd number of loops is used said 30 apertures have to be made to communicate with the base upon opposite sides of the bar. A bar of this last description may obviously be used without any lateral diaphragms, as it divides the base into induction and eduction sides which communicate with each other through the loops. Other modifications in the circulation of the heating medium through the radiator may be made by reducing the number of lateral diaphragms. Thus, for instance, if, in Fig. 1, all the lateral diaphragms 40 except the one nearest the eduction side are omitted, the circulation is also established through the loops.

What I claim as my invention is—

45 1. A plurality of like loops, each provided with an eye forming a section of the base of the radiator, combined with a bar passing through the base of the radiator and extending the whole vertical height of said eyes to 50 form a diaphragm through the base, substantially as and for the purpose specified.

2. A series of like loops, each provided with an eye forming a section of the base of the radiator, combined with a connecting-bar having apertured ends and passing through the base of the radiator for collectively securing the loops together and extending the whole vertical height of the eyes to form a diaphragm, substantially as and for the purpose described. 55

3. A series of like loops, each provided with an eye forming a section of the base of a radiator, combined with a connecting-bar passed through the base for collectively securing the loops together and extending the whole vertical height of the said eye to form a diaphragm 60 through the base and provided with transverse cut-offs, substantially as and for the purpose specified.

4. A series of like loops, each provided with an eye forming a section of the base of the radiator, combined with a bar passing through such base connecting such loops together, extending the whole vertical height of the eye and having an aperture at each end, one communicating with the steam-space on one side 75 of said loop and the other communicating with the steam space on the opposite side of said loops, substantially as specified.

5. A series of like loops, each being provided with an eye forming a section of the base of the radiator, combined with a connecting-bar through the base of said radiator, said bar forming, with integral parts of its body, suitable diaphragms within the base to establish a circulation through the loops, substantially 80 as described.

6. In combination with the loops A, provided with bosses C and joints D, arranged to form a cylindrical base connecting with the legs of the loops, the connecting-bar E, having 90 apertured head F, threaded nipple G, screw-cap H, and lateral cut-offs I, all arranged to operate substantially as described.

7. The bar E, formed with apertured ends and lateral cut offs, substantially as described, 95 and for the purpose specified.

A. WEBER.
